UNITED STATES PATENT OFFICE.

FRANCIS M. SIMONDS, OF NEW YORK, N. Y., ASSIGNOR OF ONE-HALF TO A. FILLMORE HYDE, OF NEW YORK, N. Y.

PROCESS AND APPARATUS FOR MAGNETIC SEPARATION.

Application filed October 3, 1925. Serial No. 60,151.

The present invention has relation to a process and apparatus for separating fine magnetic particles from their admixture with non-magnetic particles, and is particularly intended for the removal of iron or of its magnetic oxide from other substances as a step in the concentration of ores of various kinds. My invention finds its best embodiment in the treatment of finely ground material.

In the process of separation of magnetic particles from non-magnetic material, as hitherto practiced, it has been proposed to cause the mixed materials to move past a series of magnets whose influence is intended to divert the magnetic particles only from the common path of movement. In order to give adequate time for action by the magnets, it has also been proposed to let the material acted on move slowly past the magnets through or with water or other retarding liquid.

Where this last mentioned expedient is resorted to, it is found in practice (particularly with very fine material) that groups of magnetic particles, becoming magnetized, form clusters which imprison or entangle among them a considerable quantity of the non-magnetic material, which, in consequence, is carried over with the magnetic material and causes very imperfect separation. Another disadvantage is found in the creation of cross currents of various kinds in the liquid, whose influence is decidedly detrimental to efficient separation.

My improved process and apparatus have for their principal object the removal of these objections. In carrying out my invention, the mixed particles are carried past the separating magnets at a substantially constant and controllable speed, without the formation of detrimental cross currents or eddies, and any clusters of magnetic particles that may be found are promptly and effectively broken up, so that the non-magnetic material is not carried over with the magnetic material to an appreciable extent.

A preferred embodiment of the invention is diagrammatically illustrated by way of example in the accompanying drawings, wherein Figure 1 is a side elevation of one form of apparatus for carrying out my improved process, Figure 2, is a partial sectional view of the same, the plane of section

being parallel to the side seen in Figure 1, 55 Figure 3 is a partial vertical sectional view taken at right angles to Figure 2, Figure 4 is a partial face view of the pushing plate, Figure 5 is an edge view of the same, and Figure 6 is a partial face view of a modified 60 form of perforated plate, shown in another form in Figure 3.

The separator has an outer casing 10 made of wood, hard rubber or other suitable non-magnetic material; and against, and outside of one wall, 11, of this casing are mounted a series of magnets, preferably electro-magnets 12, as shown. These magnets may have either constant or intermittent polarization 65 as desired, and their poles may remain the same (as where excited by continuous electric current) or may be reversed (as where excited by alternating current).

I prefer to employ a cross partition 13 near the top of the casing for a purpose described hereinafter, and at the bottom the casing is divided by a partition 14 into two chambers 15 and 16 for receiving the non-magnetic and the magnetic particles, respectively. (See Figure 2.)

At the back of the partition 13 (that is on the side away from the magnets 12) the mixed powdered material is fed continuously in any suitable manner, the same being suspended in a current of water. Clear water, 85 moving at nearly the same rate is caused to flow downward in front of the partition 13. Any overflow may be discharged at one side as through the opening 17 (Figure 3). The feed preferably takes place on opposite sides 90 and outside of the two fore-and-aft partitions 18, 19. (Figure 3.)

The space above the top of the lower partition 14 is occupied by a group of parallel perforated plates 20, made of aluminum alloy or other non-magnetic material, and so constructed and mounted as to be capable of rapid reciprocating movements up and down. In order to impart these movements, I prefer to mount the successive plates upon pairs of eccentric cams 21, 22, on a shaft 23, said cams playing in slots 24 in the respective plates 20. In each pair of cams, when one of a pair is lifting its plate 20, the other is lowering its plate. Alternate plates are thus kept moving vertically in opposite directions, so long as the shaft 23 is made to revolve. This revolution may be accom-

plished by the pulley 25 and belt 26 or otherwise. Means for steadyng and guiding the plates 20 can be provided as desired, and are not shown as the invention can be more clearly exhibited by the diagrams used, which show the essentials only.

Any means for imparting adequate vibration to the plates 20 is within the scope of my invention.

10 The perforated plates 20 are provided with slots or perforations 27 (as in Figure 3) or these plates may be composed of wire mesh 28 (see Figure 6). In either case openings are afforded through which the fine material attracted by the magnets 12 may move.

15 Next to the front wall 11 is a pushing plate 29 mounted for slow up and down movement, and equipped to push downward the magnetic particles which find their way against the inner surface of said wall under the influence of the magnets 12. In this way the gathering particles are conveyed to the receiving chamber 16, and the wall 11 is kept clear for the accommodation of more 20 magnetic particles. The openings 30 in the plate 29 permit the particles to pass through to the front wall.

25 The pushing means for the attracted particles may be given a variety of forms, an example of which is shown in Figures 2, 4 and 5. Upon the forward face of the pushing plate 29 there are pivotally mounted a number of swinging scrapers 31, having lugs 32 which limit their upward movement so that they assume the position shown in 30 dotted lines in Figures 2 and 5.

35 The plate 29 is mounted upon an eccentric cam 33 on a slow moving shaft 34, turning within a suitable slot or cam opening 35 in the plate. Revolution of the shaft 34 by the pulley 36 and belt 37, or otherwise, causes a slow up and down movement of the plate 29. As the plate moves upward gravity together with the water resistance causes the 40 scrapers 31 to take the full line position in Figure 5. When the plate 29 moves downward again, the water resistance lifts the scrapers into dotted line position with their edges against the wall 11, so that they push down the particles adhering to the wall. Instead of mechanical means of pushing down the magnetic particles jets of water 45 could be used.

50 The mode of operation of my apparatus will now be clear. The mass of mingled particles suspended in water moves downward behind the partition 13 and into the space below, between the plates 20. The attractive force of the magnets 12 causes the 55 magnetic particles in the mixture to travel toward the front wall 11, the greater part of these moving in groups entangling certain quantities of non-magnetic material.

60 As these groups pass through the openings in the plates 20 they are subjected to a re-

peated chopping action which breaks the groups up again and again, thus allowing the non-magnetic particles to escape and move unimpeded down into the chamber 15. A substantially purely magnetic mass of 65 particles is thus finally brought to the wall 11 whence it is scraped into the chamber 16 as already described.

70 The rapidly vibrating plates 20 not only serve to break up the impure groups as described but act by their presence to prevent the formation of cross currents and local eddies which otherwise are apt to be formed with sacrifice of efficiency.

75 The masses which find their way to the chambers 15 and 16 respectively may be removed in any convenient manner, but I prefer to accomplish this continuously by the means illustrated. They include a screw conveyer in each chamber, shown at 38 and 39, which are rotated by pulleys 40 and 41 respectively.

80 In order to obtain a better seal and a more complete control of the discharge, I prefer to provide a downward passage 42 at 85 the exit end of each conveyer 38, 39, and to place another screw conveyer 43 therein (see Figure 3). This latter conveyer in each case may be driven by bevel gears 44, 45, 90 driven from the driving pulley of the corresponding horizontal conveyer, as shown in Figure 3.

95 It is to be understood that the above description sets forth merely an exemplification of my invention, the scope of which is not intended to be limited to the details shown and described.

100 What I claim is:

1. The process of separating magnetic from non-magnetic particles which consists 105 in causing the mixed particles to move across a magnetic field of force and subjecting the groups formed by said field to disintegrating blows as they move toward the source of the magnetic attraction.

110 2. The process of separating magnetic from non-magnetic particles which consists in causing the mixed particles to move through narrow transverse slices in a magnetic field and breaking up the groups formed by magnetic attraction as they pass from one slice of the field to the next.

115 3. The process of separating magnetic from non-magnetic particles which consists in suspending the mixture in a current of liquid moving through a magnetic field while opposing the resultant tendency to create local cross currents.

120 4. A magnetic separator comprising a container, a source of magnetic attraction and means within the container adapted to break up groups of magnetized particles while moving through the container toward the source of magnetic attraction.

125 5. A magnetic separator comprising a

wall, a source of magnetic attraction adapted to draw magnetic particles towards that wall, a pushing plate, scrapers pivotally mounted on the face thereof, and means for causing reciprocating movement of said pushing plate and scrapers.

5. In a magnetic separator, a plurality of perforated plates in combination with means for causing successive plates to move

back and forth in their own planes in contrary directions.

7. In a magnetic separator a revoluble shaft, cams thereon a number of pairs of perforated plates mounted on said cams and adapted to be reciprocated thereby.

15 In testimony whereof I affix my signature.

FRANCIS M. SIMONDS.
